COMBINED PARTS CLEANER AND CONTAINER
FOR A RECIRCULATING SOLVENTElmar K. Messinger, Huntington Station, N.Y., assignor
to Avanel Industries Inc., Huntington Station, N.Y., a
corporation of New York

Filed Dec. 28, 1966, Ser. No. 5,212

Term of patent 14 years

(Cl. D49—1)

FIG. 1 is a top view of a combined parts cleaner and container for a recirculating solvent showing my new design;

FIG. 2 is a front view;

FIG. 3 is a side view; and

FIG. 4 is a perspective view.

The fragmentary and incomplete showing of the grate-like element in FIG. 1 is so shown for ease of illustration and is understood to be representative of the appearance of the entire area within the borders as shown.

I claim:

The ornamental design for a combined parts cleaner and container for a recirculating solvent, as shown and described.
